I. COOPER.
 HOSE CLAMP AND THE ART OR METHOD OF MAKING SAME.
 APPLICATION FILED MAY 1, 1916.

UNITED STATES PATENT OFFICE.

ISIDOR COOPER, OF BROOKLYN, NEW YORK, ASSIGNOR TO OTIS-FLAGG CORPORATION, OF NEW YORK, N. Y., A CORPORATION OF NEW YORK.

HOSE-CLAMP AND THE ART OR METHOD OF MAKING SAME.

1,340,938.

Specification of Letters Patent.

Patented May 25, 1920.

Application filed May 1, 1916. Serial No. 94,561.

To all whom it may concern:

Be it known that I, ISIDOR COOPER, a citizen of the United States, residing at the borough of Brooklyn, city of New York, county of Kings, and State of New York, have invented certain new and useful Improvements in Hose-Clamps and the Art or Method of Making Same, of which the following is a specification, reference being 10 had therein to the accompanying drawings, which form a part thereof.

My invention relates to hose clamps of a type which may be made of strip metal of uniform width throughout, and the diameter of which may be varied to permit the use of the clamp on hose of varying diameters; and it further relates to a particular method of forming a metal strip of uniform width so as to avoid waste in the raw material while permitting one section of the clamp to cross the plane of another section thereof.

Heretofore, it has been endeavored to produce a single piece hose clamp which will 25 present a continuous bearing surface upon the clamp, by rolling flat metal stock upon itself, and passing one end of the clamp through an elongated opening in a wide section of the band, the opposite ends being 30 provided with radially projecting lugs having reinforcing side webs, by means of which the helix formed, as above, is drawn together to secure the desired clamping action. This form of clamp has been largely superseded 35 by a two piece clamp, because the laterally enlarged portion which must be provided to permit one portion of the band to cross the plane of the other, causes waste of metal so great as to make the cost of production prohibitive, since a continuous band 40 clamp, aside from the waste, must be longer than the combined lengths of the parts of a two section clamp. Furthermore, every size of clamp required separate tools, and 45 heretofore, no means by which the diameter of the clamp may be varied, beyond that contraction of the clamp necessary in applying to a hose, has been provided.

By my invention, I am enabled to provide 50 a one piece helical hose clamp, one portion of which crosses the plane of another, which may be made of strip metal of the same width throughout, the laterally extended opening and the lug each being so shaped as 55 to permit the lug to pass therethrough, and

avoid any tendency of the expansion of the helix causing the lug to pass through said opening in a manner to make the handling of the clamp difficult.

I also so construct the clamp that one 60 end thereof may be shortened by cutting the material adjacent the lug and forming a new lug by a bending operation by means of hand tools. I also provide means whereby the clamp may be further reduced in 65 diameter by converting it into a two part clamp having all the characteristics of a one piece clamp, with the added characteristic that it may be adjusted by the change of the relative positions of the two sections. 70

To permit the clamp to be made of strip metal, or flat wire, of the same width throughout, I employ a special method of manufacture, which avoids all waste of material at the edges of the strip, thus permitting strip metal to be used, and effecting a 75 substantial saving of material.

The invention consists of a hose clamp embodying therein the novel features of construction hereinafter set forth and described 80 and the novel method of making same, all as more particularly pointed out in the claims hereto appended.

Referring to the drawings:

Figure 1 is an elevation of one side of a 85 hose clamp embodying my invention;

Fig. 2 is an elevation of the other side thereof;

Fig. 3 is a section thereof on the line 3—3 of Fig. 1;

Fig. 4 is a view of a cut and pierced strip of which the clamp is formed; and

Fig. 5 is a view of said strip after it has been formed and is prepared for rolling upon itself as shown in Fig. 3.

Like letters refer to like parts throughout the several views.

In the embodiment of my invention shown in the drawings, *a* indicates a continuous metal strip or band rolled upon itself, with 100 one section crossing the plane of the other through a substantially diamond shaped opening *b* intermediate the ends of said strip or band. While the sides of the strip or band *a* adjacent the opening *b* project 105 therefrom, the clamp is made from material which originally was of uniform width throughout.

The opposite ends of the strip or band *a* are turned substantially radially of the 110

clamp to form lugs *c—d*, each having a bolt opening therein through which the screw bolt *e* coöperating with the nut *f* projects. This screw bolt and nut is used for contracting the clamp to secure the desired pressure on the hose. By using short lugs, the head and nut of the screw bolt reinforce said lugs, so as to avoid the necessity for side webs, which not only require additional metal stock at the sides of the lugs, but require special forming operations. Furthermore, the presence of such webs would preclude the use of the diamond shaped opening *b*, the width of which is only sufficient to permit the lug *c* to pass therethrough, and the band or strip to slide freely therein.

To permit the adjustment of the diameter of the clamp, I provide adjacent one of the lugs, as *c*, a series of bolt holes *g* so that the end of the strip or band may be shortened, and the end thereof turned to form a new lug.

To permit further adjustment of the diameter of the clamp, I form in the length thereof a series of hooks *h* and a series of openings *i* so that by cutting the strip intermediate said hooks and said openings, the clamp may be converted into a two piece clamp having all of the characteristics of the one-piece clamp, but of considerably smaller diameter. The foregoing effect is secured by lapping the end of the section having the openings *i* therein upon the portion of the strip having the hooks *h* and causing the said hooks to engage the edges of the openings *i*. In this manner the length of the strip forming the clamp may be decreased, thus resulting in the shortening of the entire clamp with a resultant decrease in the diameter thereof. In this manner it is possible to vary the size of any clamp to an extent beyond that possible by the use of the screw bolt *e* and the nut *f*.

It will be observed that all of the openings in the clamp are surrounded by the body thereof in a manner to insure such continuity of the clamping surface as to avoid possible leakage; and that the band is lapped upon itself in a manner to have the bearing face imperforate throughout substantially its entire length.

In order to make the clamp from a strip or band of uniform width throughout, I first cut the desired length from the material of the roll and then pierce it to provide an elongated slot indicated at *j* Fig. 4, also piercing the remaining openings at the same time. Following the cutting and piercing operations, I force the sides of the slot *j* outward expanding said slot *j* into a diamond shaped opening without materially stretching the metal except at the projecting point of the diamond shaped opening *b*, thus formed. I then turn the ends of the blank outward to form the lugs *c—d* and as-

semble by rolling the blank upon itself and passing the lug *c* through the central portion of the diamond.

The manner of applying the clamp to a hose and adjusting its diameter will be apparent from the foregoing description.

It is not my intention to claim broadly a one-piece hose clamp, one portion of which crosses the plane of the other to form a helix, this being old in the art. I believe it to be new, however, to provide a clamp which is so constructed as to be of substantially the same width throughout excepting as to a laterally expanded portion forming a substantially diamond shaped opening so as to permit the production of a clamp of a strip of uniform width.

Having described the invention, what I claim as new and desire to have protected by Letters Patent is:—

1. A hose clamp formed of a continuous strip or band of substantially the same width throughout and having the ends thereof turned at an angle to form straight narrow lugs having bolt openings therethrough, said strip having in the length thereof a slot with the metal on opposite sides thereof forced outwardly to form therein a substantially diamond shaped opening, said strip being wound upon itself with one end of the strip or band passed through said opening to cause one portion of the strip or band to cross the plane of another portion thereof and present a clamping area in substantially the same circular plane throughout, and take up means operative upon said lugs.

2. A hose clamp formed of a continuous strip or band of substantially the same width throughout and having the ends thereof turned at an angle to form straight narrow lugs having bolt openings therethrough, said strip having in the length thereof a slot with the metal on opposite sides thereof forced outwardly to form therein a substantially diamond shaped opening, said strip being wound upon itself with one end of the strip or band passed through said opening to cause one portion of the strip or band to cross the plane of another portion thereof and present a clamping area in substantially the same circular plane throughout, said strip or band on one side of said opening having a series of bolt openings whereby the strip may be shortened and the end thereof turned to form an end lug having a bolt opening therein, and take up means operative upon said lugs.

3. A hose clamp formed of a continuous strip or band of substantially the same width throughout and having the ends thereof turned at an angle to form straight narrow lugs having bolt openings therethrough, said strip having in the length thereof a slot with the metal on opposite

sides thereof forced outwardly to form therein a substantially diamond shaped opening, said strip being wound upon itself with one end of the strip or band passed 5 through said opening to cause one portion of the strip or band to cross the plane of another portion thereof and present a clamping area in substantially the same circular plane throughout, said strip having on one 10 side thereof a series of projections and a series of openings adapted to be engaged by said projections whereby the strip may be cut into two sections and said two sections may be united to form a continuous clamp 15 of small diameter, and take up means operative upon said lugs.

4. A hose clamp formed of a continuous strip or band of substantially the same width throughout and having the ends 20 thereof turned at an angle to form straight narrow lugs having bolt openings therethrough, said strip having in the length thereof a slot with the metal on opposite sides thereof forced outwardly to form 25 therein a substantially diamond shaped opening, said strip being wound upon itself

with one end of the strip or band passed through said opening to cause one portion of the strip or band to cross the plane of another thereof, and present a clamping 30 area in substantially the same circular plane throughout, said strip or band on one side of said opening having a series of bolt openings whereby the strip may be shortened and the end thereof turned to form an end 35 lug having a bolt opening therein, said strip having on one side thereof a series of projections and a series of openings adapted to be engaged by said projection whereby the strip may be cut into two sections and said 40 two sections may be united to form a continuous clamp of small diameter, and take up means operative upon said lugs.

In witness whereof I have hereunto affixed my signature, in the presence of two sub- 45 scribing witnesses, this 13th day of April, 1916.

ISIDOR COOPER.
